UNITED STATES PATENT OFFICE

158,412

JIGGER

Richard L. Sandefur, Central Islip, N. Y.

Application July 30, 1948, Serial No. 147,850

Term of patent 3½ years

(Cl. D36—8)

To all whom it may concern:

Be it known that Richard L. Sandefur, a citizen of the United States and a resident of Central Islip, in the county of Suffolk and State of New York, has invented a certain new, original, and ornamental Design for a Jigger, described and claimed in the following specification and shown in the accompanying drawings wherein:

Fig. 1 is a plan view of a jigger embodying the present design;

Fig. 2 is a side elevation thereof; and

Fig. 3 is also a side elevation of the jigger taken at right angles to Fig. 2.

What is claimed is:

The ornamental design for a jigger, substantially as shown.

RICHARD L. SANDEFUR.
